(57) CLAIM

The ornamental design for a single sole shoe with orange sole and stripe, as shown and described.

DESCRIPTION

The file of this patent contains at least one drawing executed in color. Copies of this patent with color drawing(s) will be provided by the Office upon request and payment of the necessary fee.

FIG. 1 is a perspective view of an embodiment of our new design of a single sole shoe with orange sole and stripe; FIG. 2 is a first side view thereof;

FIG. 3 is a second side view thereof;

FIG. 4 is a top view thereof;

FIG. 5 is a bottom view thereof;

FIG. 6 is a front view thereof;

FIG. 7 is a back view thereof;

FIG. 8 is a perspective view of another embodiment of our new design of a single sole shoe with orange sole and stripe of FIG. 1, where the orange portions are indicated using the USPTO convention of solid vertical lines for orange;

FIG. 9 is a first side view thereof;

FIG. 10 is a second side view thereof;

FIG. 11 is a top view thereof;

FIG. 12 is a bottom view thereof;

FIG. 13 is a front view thereof; and,

FIG. 14 is a rear view thereof.

The broken lines illustrating the toe elastic area, the half-moon patch, the heel stripe, and the channel on the orange sole in the above described Figures are for illustrative purposes only and form no part of the claimed design.
